UNITED STATES PATENT OFFICE.

CARL F. SWANSON, OF ST. PAUL, MINNESOTA, ASSIGNOR TO X-RAY EGG TESTER CO., OF ST. PAUL, MINNESOTA.

EGG-TESTER.

No. 879,800.

Specification of Letters Patent.

Patented Feb. 18, 1908.

Application filed July 16, 1907. Serial No. 384,037.

To all whom it may concern:

Be it known that I, CARL F. SWANSON, a citizen of the United States, and a resident of St. Paul, in the county of Ramsey and State of Minnesota, have invented a new and Improved Egg-Tester, of which the following is a full, clear, and exact description.

The purpose of this invention is to provide novel details of construction for an egg tester, which are simple and very effective in service, affording convenient means for giving mirrors employed any desired inclination from a vertical position, to reflect rays of light impinging thereon at a proper angle for illuminating eggs held in the tester for inspection.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a partly sectional side view of the improved egg tester showing different adjustments for the interior details by dotted lines; Fig. 2 is a partly sectional side view, taken at a right angle to that shown in Fig. 1 and substantially on the line 2—2 in said figure; and Fig. 3 is an enlarged, partly sectional plan view of details, taken substantially on the line 3—3 in Fig. 1.

The body portion 5 of the tester is in the form of a rectangular box having two opposite side walls 5^a, that are affixed upon the bottom wall 5^b, as shown in Fig. 2. Rectangular openings are formed in the remaining opposite sides of the body 5, which are marginally defined by transverse border strips *a*, *a'*, that form abutments against which the frames *b* of two similar mirrors 6, 6 may impinge, said frames having suitable back boards for the support of the mirrors.

The frames of the mirrors 6 are rectangular, and at central points on the upright members *b'* of each frame, the perforated end portions of two similar link-bars *c*, *c* are pivoted by screw-studs *d*, as indicated in Fig. 1 and also for one link-bar, in Fig. 3.

Upon opposite ends of the link-bars *c*, *c*, the end portions of two similar link-bars *e*, *e* are lapped and pivoted, as shown at *e'* in Fig. 1. The remaining ends of the link-bars *e*, *e* are perforated laterally and lapped

together, receiving journal studs *g* that are fixed in the permanent side walls 5^a at their centers and therefore oppositely.

It is to be understood that as the connections *c*, *c* and *e*, *e* are similar for each mirror-frame *b*, the latter will be supported on the links and their pivots, so as to be adapted for adjustment, either to close the openings in the sides of the body 5, or be inclined as indicated by dotted lines in Fig. 1, as will be further explained hereinafter.

Upon the level upper edge of the rectangular body 5 a cover or hood 7 is mounted, it comprising a four-walled structure having the lower end thereof equal in dimensions 70 with those of the body 5, and from said lower end having its walls converged toward the upper end, thus giving said hood the form of a pyramid with the pinnacle thereof removed. The upper open end of the hood 7 75 has two opposite edges *h* concaved and also scalloped, as shown at *h'*, thus permitting a person to completely close the open end if the face of the person is imposed upon said edges, which is important, as it prevents the 80 entrance of light at the top of the tester, which would detrimentally affect the testing operation.

The lower edge of the hood 7 is hinged at one side, as shown at *i*, and a hook and staple 85 or equivalent securing means is provided at the opposite side, as shown at *m*, thus detachably holding the hood 7 on the body portion 5. For convenience in handling, a bail-handle 8 is mounted upon the hood 7 90 near its upper end.

The free top edge of the body section 5 is rabbeted, as at *k*, and forms a seat whereon a holder-plate *A* of an egg-lifter of any preferred construction is removably seated when 95 the tester is in use, said plate supporting eggs that are to be inspected by one looking down upon the eggs, which are exposed to rays of light reflected upwardly from below the plate and eggs.

The improved egg tester affords means for utilizing natural light, such as the rays of the sun, or artificial light, if natural light is not available.

It will be seen that the mirrors 6, 6 may be 105 given various inclinations, so as to receive light-rays and reflect such rays upwardly. For example, one or both mirrors may be inclined outwardly and downwardly, near the bottom wall 5^b, as shown broken and in 110

dotted lines in Fig. 1, thereby adapting them for receiving light from outside of the box body 5 and reflecting it upward through the eggs. Artificial light, such as a brilliant light from a lamp in a dark room, may also be employed and the rays therefrom that impinge upon the mirror or mirrors as the case may be, will be reflected upwardly.

The mirrors may be arranged to incline 10 toward each other at their lower edges, and an electric lamp 9 be employed for illuminating the interior of the box body 5, said lamp being positioned between the inclined mirrors, as shown in Fig. 1. The mirrors 6, 6 15 are to be disposed vertically and against the border-strips a, a' when the tester device is not in service, which may be effected by an adjustment of the mirrors and their controlling link-bars c, c and e, e , as shown by full 20 lines in Figs. 1 and 3.

In order to expedite the removal of a plate A that is part of an egg-lifter, after the eggs thereon have been tested, a short shaft n is journaled in one side 5^a , near its upper edge, 25 an arm n' being secured on the inner end of said shaft at right angles thereto, the arm having sufficient length for its impingement on the lower side of the plate A, and effect a sufficient elevation of the latter to permit it 30 to be manually grasped and raised from the body 5. On the outer end of the shaft n a thumb-piece or cross-arm n^2 is formed, which enables a turning movement of the shaft n , and thus causes the arm to be elevated for 35 the purpose described.

Having thus described my invention, I claim as new and desire to secure by Letters Patent:

1. An egg-testing device, embodying a 40 hollow four-sided body having an opening in each of two opposite sides, and mirrors adjustably supported in the body, adapted for closure of the openings or for receiving inclinations in the body.

45 2. An egg-testing device, embodying a

hollow four-sided body having an opening in each of two opposite sides, two mirrors, and adjustable link-bars pivoted upon the body and upon the mirrors, that by adjustment of said link-bars may effect the closure 50 of the openings or be given changeable inclinations in the body.

3. An egg-testing device, embodying a hollow four-sided body having an opening in each of two opposite sides, a mirror adjustably supported in the body and adapted for inclination at the opening, a hood having upwardly converged walls and a sight-opening 55 at the upper edge of said hood.

4. An egg-testing device, embodying a 60 four-sided hollow body, two opposite sides thereof having an opening in each, two framed and backed mirrors that may close these openings, and two pairs of link-bars, each pair pivoted together at their lapped 65 ends and at the remaining ends respectively pivoted upon the side edges of the mirror-frames and upon the walls of the body at opposite points, whereby the mirrors may be given different inclinations from a vertical 70 plane, for the reflection of impinging rays of light upwardly.

5. An egg-testing device embodying a rectangular hollow body having a rabbeted upper edge and having an apertured egg- 75 holder plate seated on said rabbeted edge, a rock-shaft journaled in a side wall of the body, near the holder-plate, an arm on an end of said shaft, and means for turning the shaft, for impinging an end of the arm on the 80 holder-plate, thus raising said plate and permitting its manual removal.

In testimony whereof I have signed my name to this specification in the presence of two subscribing witnesses.

CARL F. SWANSON.
